Primary Examiner — Prabhakar Deshmukh

(57) **CLAIM**

The ornamental design for an attachable electronic media holder, as shown and described.

DESCRIPTION

FIG. 1 is a perspective view of an attachable electronic media holder showing an embodiment of my design;

FIG. 2 is a back elevational view of an attachable electronic media holder;

FIG. 3 is a front elevational view of an attachable electronic media holder;

FIG. 4 is a right side elevational view of an attachable electronic media holder;

FIG. 5 is a left side elevational view of an attachable electronic media holder;

FIG. 6 is a bottom plan view of an attachable electronic media holder;

FIG. 7 is a top plan view of an attachable electronic media holder; and,

FIG. 8 is a left side elevational view of an attachable electronic media holder that is attached to a collapsible baby bouncer.

The collapsible baby bouncer shown in broken lines is for illustration only and forms no part of the claimed design.

1 Claim, 8 Drawing Sheets
